UNITED STATES PATENT OFFICE.

WILLIAM L. BLACK, OF FORT MCKAVETT, TEXAS.

ANTIFRICTION HOLLOW-TUBE SUCKER-ROD FOR DEEP WELLS.

1,281,756.

Specification of Letters Patent. Patented Oct. 15, 1918.

Application filed February 26, 1918. Serial No. 218,712.

To all whom it may concern:

Be it known that I, WILLIAM L. BLACK, a citizen of the United States, and resident of Fort McKavett, in the county of Menard 5 and State of Texas, have invented certain new and useful Improvements in Antifric-
tion Hollow-Tube Sucker-Rods for Deep
Wells, of which the following is a specifica-
tion.

10 The present invention relates to sucker rods for pumping oil, water and other liquids from deep wells, and aims to provide novel and improved yet simple and inexpensive means for coupling the tubular sections 15 of the sucker rod together and guiding said rod with little or no friction in the well casing or tube.

The invention has for its object the provision of a simple and effective device for 20 coupling the tubular sections of the sucker rod together, and provided with simple and efficient anti-friction means for guiding the sucker rod for reciprocation in the well.

This invention is an improvement over the 25 devices shown in my former Patents Nos. 467,494, 484,947, 712,486, 712,487, 712,488,
712,901, and 735,200.

With the foregoing and other objects in view, which will be apparent as the invention 30 is better understood, the same resides in the construction and arrangement of parts hereinafter described and claimed, it being understood that changes within the scope of what is claimed can be made without departing from the spirit of the invention.

The invention is illustrated in the accompanying drawing, wherein—

Figure 1 is a longitudinal section of the 40 coupling and roller guide.

Fig. 2 is a side elevation thereof.

In the drawing, the numeral 1 designates the casing or tube of a deep well, and the numerals 2 and 3 designate two tubular sections of the sucker rod which reciprocates in the casing 1 for pumping the oil, water or other liquid as usual.

The coupling is designated generally by the numeral 4, and embodies a vertical tubu- 50 lar or hollow body 5 of suitable material and of larger diameter than the sucker rod and slightly less diameter than the casing 1.

The upper and lower ends of the body 5 are contracted, as at 6, to provide the reduced 55 open ends or bosses 7 which are internally screw threaded for the threaded reception

of the adjacent ends of the sucker rods sections 2 and 3, thus coupling said sections together.

Disposed within the body 5 of the coupling are a plurality of vertically spaced guide rollers 8, there being two as illustrated although more can be used. These rollers are arranged in different vertical planes at an angle with one another, and said rollers 60 are mounted on the axles or pins 9 having heads at one end and their other terminals threaded within the walls of the body 5, cotter pins or retaining elements 10 being preferably engaged through the threaded terminals of the axles to prevent loosening thereof. The walls of the body 5 are provided with longitudinal slots 11 through which the peripheries of the rollers 8 project slightly from the opposite sides of the 70 coupling. The rollers 8 are of slightly larger diameter than the body 5 to project therefrom, but of slightly less diameter than the internal diameter of the well casing 1, so that the rollers will be out of contact with 80 the casing when the sucker rod is concentric therein.

With the present construction, the hollow or tubular sucker rod sections have their ends opening into the coupler which is tubular or hollow, and this permits of the liquid flowing through the sucker rod and coupler as well as on the exterior thereof, thus increasing the capacity of the pump to the maximum, because of the maximum cross 90 sectional area of the column of liquid within and without the sucker rod.

The sucker rod is at all times kept at the center of the casing by the rollers, for should the sucker rod tend to shift laterally toward 95 any side, one or both of the rollers will contact with the casing. Said rollers will reduce friction between the sucker rod and casing. The axles of the rollers can be of comparatively large diameter, so as to insure 100 great strength and wearing ability. This device therefore provides for economy by increasing the capacity of the pump and decreasing wear and tear. Furthermore, the hollow formation of the coupler and slots 105 prevents the accumulation of sand, grit and the like adjacent to the rollers, thus keeping the device clear.

It is preferable to have lock nuts 12 on the rod sections 2 and 3 to bind against the 110 ends of the coupler and avoid loosening of the parts.

Having thus described the invention, what is claimed as new is:

- 5 1. A sucker rod guide and coupling embodying a slotted vertical body having means to connect the spaced ends of tubular sucker rod sections, said body being hollow for permitting the flow of liquid between said sucker rod sections and rollers mounted in the body in different vertical planes at 10 an angle with one another and projecting outwardly through the slots of the body.
- 15 2. A sucker rod guide and coupling embodying a hollow vertical body having side slots and open ends for the attachment of spaced tubular sucker rod sections to connect them and permit the flow of liquid therein, and, rollers mounted within the body in different vertical planes at an angle with one another and projecting outwardly 20 through said slots from the sides of the body.
- 25 3. A sucker rod guide and coupling embodying a hollow body having slotted sides and open ends for the attachment of the ends of spaced tubular sucker rod sections to connect them and permit the flow of liquid therein, and anti-friction guiding means mounted within the body and projecting from the sides thereof through the slots.
- 30 4. A sucker rod guide and coupling embodying a hollow body having slots in its sides and reduced open ends for the attachment of spaced tubular sucker rod sections to connect them and permit the flow of liquid therein, and rollers mounted within the body and projecting from the sides thereof through said slots.
- 35 5. A sucker rod guide and coupling embodying a hollow vertical body having open ends for the attachment of spaced tubular sucker rod sections to connect them and permit the flow of liquid therein, vertically

spaced rollers within the body in different vertical planes at an angle with one another, the sides of the body having slots from which the rollers project, and axles for the 45 rollers supported by the walls of the body.

6. The combination with spaced tubular sucker rod sections, of a hollow coupling connecting them for the flow of liquid therein and having side slots, and anti-friction means housed within the coupling and extending out through the slots to guide it in the well.

7. The combination with spaced tubular sucker rod sections, of a hollow coupling 55 connecting them for the flow of liquid therein and having side slots, and vertically spaced anti-friction guiding means mounted within the coupling and projecting from the sides thereof through the slots.

8. The combination with spaced tubular sucker rod sections, of a coupling embodying a hollow body having slotted sides and open ends attached to said sections to connect them and permit the flow of liquid 65 therein, and rollers mounted within the body and projecting from the sides thereof through the slots.

9. The combination with spaced tubular sucker rod sections, of a coupling therefor 70 embodying a hollow body of larger diameter than said sections and having reduced open ends attached to the adjacent ends of said sections to connect them for the flow of liquid therein, rollers within the body, the 75 walls of the body having slots through which said rollers project, and axles for the rollers supported by said walls.

In testimony whereof I set my hand this 18th day of February, 1918.

WILLIAM L. BLACK.
